VARIABLE SPEED FAN DRIVE

Lawrence D. Suttle, Detroit, Mich., assignor to
Robert J. Schaffer, Detroit, Mich.

Application January 27, 1955, Serial No. 484,345

8 Claims. (Cl. 123—41.12)

This invention resides in the field of fan drives of the disconnectable or slip-coupling type for use with or on the cooling system of a vehicle's internal combustion engine or the like.

A primary object of my invention is a new and improved fan drive adapted to provide slippage between the fan and the engine at a predetermined speed so that at high speeds the fan will not steal power from the engine.

Another object is a fan drive of the above type adapted to be driven at the same speed as the engine up to a predetermined speed after which, as the engine speed increases, the fan will remain approximately at the predetermined speed.

Another object is a drive of the above type which can be used for other accessories commonly found on such an engine or vehicle.

Another object is a fan drive of the above type in the form of an attachment usable on or with conventional engines.

Another object is a fan drive of the above type constructed so that less horsepower will be required to drive it.

Another object is a fan drive of the above type which is quieter in operation at the higher engine speeds.

Another object is a fan drive of the above type responsive to ambient temperature so that in winter the engine will be allowed to heat up more rapidly, and in summer the engine will be cooled quicker.

Another object is a fan drive of the above type with opposed friction elements to provide slippage between the fan and its drive and including means for cooling the friction elements at a rate relative to the engine speed.

Another object is a fan and fan drive of the above type which runs at all times that the engine is running, but will not exceed a predetermined rotative speed regardless of the engine speed.

Other objects will appear from time to time in the ensuing specification and drawings in which:

Figure 1 is a side view, partly in section, of my new and improved fan drive;

Figure 2 is a section of a modified form of fan drive;

Figure 3 is a front view partly in section of the fan drive shown in Figure 1;

Figure 4 is a detail view;

Figure 5 is a side view, partly in section, of a variant form; and

Figure 6 is a front view, with parts broken away, of the Figure 5 variant form.

In Fig. 1 a suitable pulley or sheave 10 is adapted to be driven by the usual engine fan belt, not shown, or any other suitable drive. The pulley is connected to a member 12 to drive a conventional water pump through a water pump shaft 14 and 16.

A body member 18 is mounted over the forward end of the water pump shaft by a plurality of suitable bolts 20 or the like. The body member is formed into a projecting shaft or stub 22 at its forward end which carries

2

a suitable fan 24. The fan 24 is rotatably mounted about the stub 22 through a suitable ball bearing unit 26. The bearing is held in a cage formed by the inner part of the fan proper, as at 28, and a cylindrical portion 30 of a platelike member 32 which is formed upwardly and rearwardly into a suitable sheave or pulley 34 and has a lip 35 at its inner edge. The member 32 also carries a circular friction member or ring 36 on its inner surface; the fan, member 32, and friction member 36 being held together by a suitable number of bolts 38 or the like, which are spaced around the center of the fan.

A cuplike member 40, mounted on the body member by the bolts 20, is flanged at 42 at its outer edge and carries a second friction element 44 which opposes the friction ring 36 on the fan. The friction element 44 is provided with a suitable number of radial slots 46 as shown in Fig. 3, and the hub or inner portion of the fan is provided with a suitable number of openings 48 which extend through the fan, member 32, and friction ring 36, so that air can enter the space or chamber between the fan and the body member.

The fan and its bearing unit 26 are adapted to slip on the stub or shaft 22 in an axial direction, and a sliding collar 50 around the stub engages the inner race of the bearing. A spring 52, held by a snap ring 54 which bears against a shoulder 56 near the end of the stub or shaft 22, biases the collar and ball bearing unit, as well as the fan, rearwardly so that the friction plate 36 will engage the friction segments or elements 44 at all times.

In Fig. 1 I have shown the friction elements disposed in a plane generally at right angles to the axis of the body member and fan; however, the friction elements could be inclined rearwardly, as shown in Fig. 2 or forwardly if desired.

In Figure 5 I have shown a variant form in which the sheave or pulley 58 is mounted on a member 60 with a suitable spacer 62 or the like, the member 60 being secured to the water pump shaft by one or more suitable pins 64. A cup-like member 66 is secured to the body member 68 by a suitable number of bolts 70 or the like, the bolts extending through the cup-like member 66, the body member 68, the spacer 62 and the member 60.

The flanged portion 72 of the cup-like member carries a plurality of friction elements 74 which are disc shaped, as shown in Figure 6 and are secured to the flange by a suitable rivet or pin 76 countersunk as at 78 to prevent wear.

The fan 80 is mounted on a friction plate 82 by a suitable number of rivets 84 or the like. The inner portion of the friction plate is formed at 86 to retain the ball bearing unit 88 mounted on the shaft or stub 90. The fan and friction plate are provided with aligned openings 92 and 94 so that air will be admitted to the inside of the cup shaped member.

A suitable collar 96 on the shaft is biased against the inner race of the bearing by oppositely disposed Belleville bimetallic spring type discs 98 which abut a suitable lock nut 100 threaded on the stub shaft and held in position by a suitable lock washer 102. As shown in Figure 6, the Belleville springs are disc shaped and are provided with radial slots 104 to allow for expansion and contraction.

The use, operation and function of my invention are as follows:

I have shown and described a fan drive for use with the engine of a vehicle. The fan's primary purpose is to cool the engine at the lower speeds. At the higher speeds the moving air created by the vehicle cools the engine substantially and the fan is not so important.

To get proper cooling of the engine at the lower speeds the fan has to be relatively large in capacity and size. At the higher speeds the noise created by this large fan and

the power absorbed by it become excessive. The fan, in a sense, at the higher speeds steals excessive power from the engine which otherwise could be used to propel the vehicle. Clutch-type devices are known which disconnect the fan entirely from the engine at a predetermined engine speed.

In my new and improved fan drive, at a predetermined speed, slippage occurs between the fan and its drive through its friction elements so that, even though the engine reaches higher speeds, the fan will remain at a lower speed.

In my invention a body member having a friction element is attached to the water pump shaft to be driven by the engine and is referred to as the driving member.

A fan is rotatably mounted on the body member and carries another friction element which opposes the first friction element on the body member. Axial movement or slippage is permitted between the fan and body member so that the pressure between the friction elements can be varied. A spring biases the friction elements together so that a positive rotative drive is established between the body member (the driving member) and the fan (the driven member).

At the lower speeds no slippage will occur between the friction elements so that the fan will be driven at the same speed as the engine. At the higher speeds the fan will tend to thrust forward and slippage will occur between the friction elements because the fan is slidably mounted on the body member. The forward thrust of the fan is opposed by the spring, and the tension exerted by the spring determines the particular speed at which slippage first occurs. As the engine attains speeds in excess of this particular speed, slippage will continue between the friction elements and the fan will tend to remain at a relatively constant speed which is independent of the engine speed.

In setting the top speed of the fan, the tension of the spring, the material used for the friction segments, the material of the plate opposing the segments, the size and thrust of the fan, and other factors must be taken into consideration.

The spring can be formed as a bimetal element so that the force exerted by it will vary dependent upon the ambient temperature. This is particularly advantageous due to the change in temperature from one season to another. For example, in winter when the outside temperature is low, it is desirable that the engine be allowed to warm up as fast as possible, and the fan's cooling effect should be reduced. Therefore the bimetal spring should react to the lower temperatures by reducing its force or thrust so that slippage will occur at a lower speed. In the summer when the temperatures are relatively high, more engine cooling is required, and the bimetal spring should respond to the high temperatures so that its force will be increased to cause slippage to occur between the fan and the body member at a higher predetermined speed. Therefore the bimetal spring should be arranged and constructed so that it will exert more force at high temperature and less force at low temperature.

Whereas I have shown and described my invention as applied to a fan for cooling the engine, it should be understood that various other accessories on modern automobiles also do not require the high engine speeds. A suitable drive, such as through the pulley 34 and a belt, not shown, could be provided running to these accessories so that they too would not be driven in excess of the predetermined speed.

While I have shown the friction surfaces as lying in a plane generally at right angles to the axes of the body member and fan, as in Fig. 1, it should be understood that the plane of these surfaces could be inclined, as in Fig. 2, to increase the effective frictional contact area. At the same time the angle of inclination could be in the opposite direction from that shown in Fig. 2.

The friction element 44 carried by the body member

is divided by slots into a plurality of frictional segments with the friction ring or disc 36 on the fan bridging these slots. A plurality of suitably disposed openings are provided near the center of the fan so that air is admitted to the space between the body member and fan. This air will flow outwardly through the slots in the friction members to carry away the heat generated due to friction. Additionally, this air stream will also carry away undesirable dirt and dust. It is very desirable that these slots be formed in the friction element carried by the driving member because the driving member will reach the higher speeds of the engine which the driven member does not reach. Thus the friction elements carried by the driving member also has a fan action at higher speeds, and the air forced through the slots will effectively carry away the heat generated by friction between the elements.

The unit could be manufactured and packaged as an attachment including the fan, friction elements and body member, which could easily be attached to the shaft of the water pump on a conventional automobile. Such an attachment could either have or be without the accessory driving sheave 34.

In the modified form of Figures 5 and 6, the chamber between the cup member and the fan receives air through the openings 92. The disc shaped friction elements 74 perform a turbine action in expelling the air from the chamber and additionally increase the fan's grit and dirt clearance characteristics. Furthermore each disc shaped friction pad can rotate about its rivet connection 76 without changing its friction effect. This serves to uniformly wear each of the friction pads.

The adjusting nut 100 can be used to change the biasing force of the Belleville springs. The thermally responsive spring has the same action as the spring in the previous embodiment under changing temperature conditions. It should be noted that the springs are in direct metal to metal contact with the shaft so that the heat of the engine will be directly conducted to the thermally responsive spring. When the engine is cold, the pressure exerted by the springs will be less and the cooling effect of the fan will be decreased due to the increased slippage, and vice versa.

Whereas I have shown and described the preferred form and several modifications of my invention, it should be understood that various other changes could be made. For example, in Fig. 3 I have shown a three-bladed fan; however, any number of blades could be used as in Figure 6. The second pulley for driving a suitable accessory is not absolutely necessary, although I have found it desirable. The accessory to be driven by this pulley, of course, is optional and could be the compressor for an air-conditioning unit, the power-steering drive, the generator, or any suitable accessory. It should be understood that the plane of the friction elements in Fig. 2 could be inclined in either direction. The same is true of Figure 6. The spring could be in the form of a leaf, a coil, or a suitable combination. I therefore wish that my invention be unrestricted except as by the appended claims.

60 I claim:

1. In a drive for use on an engine driven vehicle or the like adapted to drive an accessory such as a generator, air conditioning compressor, and the like, a body member adapted to be driven by the engine of the vehicle, a fan member rotatably mounted on the body member, axially opposed friction elements on the fan and body member, means for causing slippage between the friction elements above a predetermined speed including a slideable mounting for the fan on the body member, and an accessory connection on the fan.

2. The structure of claim 1 characterized by and including yielding means for biasing the friction elements together.

3. In a fan drive for an engine driven vehicle cooling system or the like, a body member adapted to be driven

by the vehicle's engine, a fan rotatably mounted on the body member, friction elements between them, means for preventing slippage between the friction elements up to a selected rotative speed and for thereafter initiating slippage, and means responsive to ambient temperatures for changing the selected rotative speed below which slippage does not occur and above which slippage does occur.

4. The structure of claim 3 in which said last mentioned means includes a bimetal element.

5. In a fan drive for an engine driven vehicle cooling system or the like, a body member adapted to be driven by the vehicle's engine, a fan on the body member, friction elements between them, means for preventing slippage between the friction elements up to a selected rotative speed, and means responsive to ambient temperatures for changing the selected rotative speed at which slippage starts.

6. In a drive mechanism for use on an engine driven vehicle or the like, a body member adapted to be driven by the engine of the vehicle, a fan member mounted on

the body member for both rotary and axial movement, axially opposed friction elements between the fan and body member, means for causing slippage between the friction elements above a predetermined speed, and means for directing an air flow through the axially opposed friction elements to remove the heat developed due to the slippage.

7. The structure of claim 6 further characterized by and including yielding means for biasing the friction elements together.

8. The structure of claim 6 further characterized by and including means responsive to ambient temperatures for changing the predetermined speed above which slippage begins.
